UNITED STATES PATENT OFFICE.

JAMES BRUCE MASON, JR., OF NASHVILLE, TENNESSEE.

LEAD PENCIL.

Application filed February 21, 1921. Serial No. 446,613.

To all whom it may concern:

Be it known that I, JAMES BRUCE MASON, Jr., a citizen of the United States, residing at Nashville, in the county of Davidson and 5 State of Tennessee, have invented certain new and useful Improvements in Lead Pencils, of which the following is a specification.

This invention relates to lead pencils of the kind in which the lead is contained within a 10 casing and is propelled or fed when required through a suitable guide and through a pointed end or nozzle in such manner that the outer end of the lead shall project only a short distance beyond the tip of the nozzle 15 so that while sufficiently exposed, for writing purposes, it is not apt to break.

Pencils of this general class have heretofore been provided with a magazine in which 20 spare leads are stored in order that when one lead has been used up to a considerable extent another lead may be brought into operative 25 position.

According to my invention I provide pencils of the class above referred to with a magazine 30 for spare leads, and said magazine is associated with means whereby a fresh lead may be transferred from the magazine to working position without opening the pencil case and without disconnecting any of its 35 parts.

In my application for Patent No. 434,883, filed Jan. 4, 1921, I have shown, described and claimed a pencil of this general kind, but the mechanism shown in the accompanying 40 drawings is different in detail from the mechanism shown in said application.

Figure 1 shows a longitudinal, central section through a pencil embodying my present 45 improvements.

Figure 2 is a view on an enlarged scale and in transverse section on the line 2-2 of Fig. 1.

Figure 3 is a similar sectional view, showing the parts in a different position.

Figure 4 shows various parts of the lead feed mechanism withdrawn from the casing and detached from each other.

Figure 5 shows in longitudinal section a modified form of pencil.

Figure 6 shows an elevation of some of the parts shown in Fig. 5.

The tubular casing A is divided about midway between its opposite ends by a partition 50 a which may be applied in any suitable way.

The upper part of the tubular casing is 55 formed on its interior with screw threads a',

the grooves and ridges of which are purposefully made quite shallow, as shown. The upper or outer end of the casing is closed by a screw cap B between which and the end of 60 the casing washers b, b' are interposed. The washer b' may be made of metal, while the washer b is preferably made of rubber, leather or similar material and should be relatively thick.

The plunger C consists of a rod, preferably made of piano wire or some such material having great rigidity and yet having elasticity. The inner or lower portion of the rod is straight, while the upper or outer end is 70 formed with a coil c' which is of such shape and size as to firmly but yieldingly engage the screw threads a' of the casing. The rod C extends through the partition a and is turned in the casing by means of a slotted bar 75 D which extends through the cap B and is provided with an operating knob d. The soft washer b fits the bar D tightly and produces such friction thereon that while the bar may be freely turned and freely moved endwise 80 it is prevented from turning or moving endwise accidentally. At its inner end the bar D is provided with a collar or flange d' adapted to abut against the partition a. The slot d' extends inward beyond the center of 85 the bar and the rod C is adapted to move longitudinally therein in the longitudinal axis of the casing. The coil c' extends from the upper end of the rod through the slot d' and then around the bar in the manner 90 clearly shown in the drawings, the parts c' of the coil being adapted to move longitudinally in the slot, while the curved portion of the coil surrounding the bar D is adapted to move longitudinally thereon.

By the construction shown, the plunger may be gradually moved endwise through the partition a by merely turning the knob d and it may also be moved in the opposite direction by reversing the movement of the 100 knob. The construction is likewise such that the plunger may be retracted by a quick sliding movement because of the shallow nature of the screw thread and the yielding condition of the coil which forms part of the 105 plunger. The devices just described are shown, described and claimed in my application for patent above mentioned.

The lower part of the tubular casing A carries a nozzle E which is removably connected with the casing by means of screw threads e. The nozzle is hollow and tapered.

as shown, the tip e' being formed with an orifice through which the lead x extends and through which it is fed. The hole is of just sufficient size to permit the lead to move 5 freely endwise without undue lateral strain. Just inside the tip e' I provide a screw plug F, similar to that shown in my before-mentioned application, through which the lead extends. This plug F serves to guide the 10 lead just before it enters the tip of the nozzle.

The magazine in which the spare leads are stored, and which contains the lead in use, is located in the lower portion of the tubular casing within a chamber G. This magazine 15 comprises a slotted, tubular member H having a tapered upper end h which enters a correspondingly tapered hole in the partition a and a lower portion h' which extends into the nozzle E. As shown in Figs. 2, 3 and 4, the member H is provided with a wing L located on one side of the slot l. It extends from one edge of the slot to the inner wall of the casing A and it guides the leads x to the central portion of the magazine. 20 The wing L may be attached to the member H in any suitable way. Preferably the member H is surrounded by a sheet metal part H' which carries the wing.

In the form of the invention shown in 30 Figs. 1-4, inclusive, the magazine is held stationary in the casing A, the end h of the member H being made to tightly fit the hole in the partition a.

M indicates a lead feeder which operates 35 as hereinafter described to automatically feed a lead into the central part of the magazine in line with the nozzle opening. This feeder comprises a bar m (Fig. 4) secured at its upper end to a ring m' and at its lower 40 end to a ring m². The ring m' surrounds the upper part of the member H and the ring m² surrounds the lower part of said member. These rings are so mounted that they may be turned about the axis 45 of the member H. The upper ring m' is connected by means of a coiled spring n to a split ring o applied to the upper end of the part h of the member H. This split ring is made to tightly fit the part h so that 50 it cannot turn thereon when once adjusted and forced into position.

By this construction, it will be observed, the feeder as a whole may be turned about the axis of the magazine. When turned in 55 one direction the spring n will be wound up and if then arrested the feeder will be held under spring tension.

The lower or outer portion of the bar m is tapered, as indicated at p, to facilitate the 60 entrance of the lead, the lower or outer end of the bar being adjacent an opening q in the ring m².

When the magazine is empty or needs re-plenishing the nozzle is removed and the 65 leads, one at a time, may be inserted through

the opening q and as they bear against the the incline p of the rod the feeder as a whole (the bar and the rings) will be turned about the axis of the pencil, in the manner indicated in Figs. 2 and 3. Ordinarily there are 70 three leads always in the pencil. Figure 3 illustrates how the next lead is inserted. The construction is such that the feeder M may come close to the lip L but when a lead is inserted the feeder is forced away from 75 the lip and a new lead assumes its position in the magazine, namely, the position shown in Fig. 3. When the next lead is inserted it will enter between the lead lettered x in Fig. 3 and the feeder M, and so on until the magazine is filled or partially filled, as shown in Fig. 2. The spring n is thus put under tension which is exerted in the manner indicated by the arrows in Figs. 2 and 3. The manner of filling the magazine is somewhat 80 similar to that shown in my application before mentioned.

In using the pencil, when thus supplied with leads, the central lead is fed forward, as required, by turning the knob d which turns the bar D, in turn revolving the plunger and the latter is moved outwards towards the nozzle and operates on the central lead, thus causing it to be fed through the nozzle. After the lead has been used up to a con- 95 siderable extent and a fresh lead is required, the coil c' will be in contact with the flange or collar d' or in close proximity thereto so that by pulling the knob d away from the end of the casing the plunger will 100 be withdrawn through the end of the magazine. As soon as it is thus withdrawn the lead which was next adjacent to said central lead will be automatically moved into the central position by the spring n which operates to turn the feeder M in the direction shown by the arrows in Figs. 2 and 3.

It will be observed that the operation of bringing a fresh lead into position requires no slow turning movement of any part of the pencil. The collar d' engages the coil c' and moves it outward without turning, the coil yielding sufficiently to easily clear the screw threads of the casing. Of course when fine adjustment is desired the plunger may 105 be retracted gradually or to a slight extent by properly turning the knob.

From a practical standpoint it will be seen that the first user of a pencil of the kind above described and shown will have 110 very little trouble in operating it or in re-charging it for a considerable time. It is only necessary to operate the knob d to feed the lead forward when required and this lead will last a considerable time. 125 When the lead fails to feed the user merely pulls the knob outwards away from the casing and a fresh lead will then automatically move into place before the knob can be returned and as soon as the knob is re- 130

turned the pencil is in condition for use for another long period. A large number of leads may be held in the magazine thus prolonging the use of the pencil for an indefinite period, but when the leads are exhausted the operation of refilling the magazine is a very easy one, it being only necessary for the user to withdraw the nozzle E and pass leads one at a time through the opening *q*, the leads being automatically guided into place as the operation of inserting the leads proceeds. It is not necessary to entirely fill the magazine as the insertion of one additional lead will put the magazine in operative condition, but of course it is preferable to insert a plurality of leads when the pencil is being recharged.

It will be observed that the plunger C is so limited in its outward movement that its does not entirely expel the lead *x* through the nozzle so that there is always some lead in the pencil ready for use before a fresh lead is brought into operative position below the plunger.

In Figs. 5 and 6 I have shown a modification in which the construction is such that both the magazine and the feeder are movable about the longitudinal axis of the pencil and are both spring-actuated. Such parts as are similar to those shown in Figs. 1-4, inclusive, are correspondingly lettered. Practically the only difference in this mechanism is that the upper end of the member H is not engaged with the partition *a* but terminates below it. In the construction shown, the feeder and the magazine proper or member H move in opposite directions; that is to say, when a lead is inserted in the manner indicated in Figs. 2 and 3, and assuming that the parts H and M are connected by a coiled spring *n* in the manner before described, it will be clear that when a lead is inserted, as indicated at *x* Fig. 3, the feeder M and the member H will be moved in opposite directions or at least are free to move in opposite directions, both being held in contact with the lead or leads by the spring.

I claim as my invention:

1. A pencil comprising a tubular casing having a nozzle at one end through which the lead is fed and having a plunger for advancing the lead in the pencil, a magazine for storing leads within the tubular casing comprising a longitudinally slotted member, and a lead feeder within the casing

rotatable about the axis of the casing and around said slotted member and spring-actuated in one direction.

2. A pencil comprising a tubular casing 60 having a nozzle in one end through which a lead is fed, and having a plunger for advancing the lead in the nozzle, a magazine for spare leads within the tubular casing, and a feeder within the casing having 65 an outer inclined end and which is mounted to turn about the axis of the magazine and which is spring-pressed in one direction.

3. A pencil comprising a tubular casing having a nozzle at one end through which 70 a lead is fed and having a plunger for advancing the lead in the nozzle, a magazine for storing spare leads within the tubular casing which is adapted to turn about the axis thereof, a lead feeder within the 75 casing also adapted to move about said longitudinal axis, and a spring connecting the feeder with the magazine.

4. A pencil comprising a tubular casing having a nozzle at one end through which 80 a lead is fed and having a plunger for advancing the lead in the nozzle, a slotted magazine member carrying a lip, a lead feeder comprising upper and lower rings and a connecting bar, a spring connected 85 with the feeder, and means for connecting said spring with the magazine member.

5. A pencil comprising a tubular casing having a nozzle at one end through which a lead is fed and having a plunger for advancing the lead in the nozzle, a slotted magazine member having a guide at its outer end for the lead, a lead feeder comprising upper and lower rings and a connecting bar, a spring attached to the upper 95 ring, and a collar to which the opposite end of the spring is attached and which is connected with the upper portion of the magazine member.

6. A pencil comprising a tubular casing 100 having a nozzle at one end through which the lead is fed and provided with means for advancing the lead in the pencil, a magazine for storing leads within the tubular casing comprising a longitudinally slotted member, 105 and a lead feeder within the casing rotatable about the axis of the casing and around said slotted member, and spring actuated in one direction.

In testimony whereof, I have hereunto 110 subscribed my name.

JAMES BRUCE MASON, Jr.
